CLAIM

The ornamental design for a bandage, as shown and described.

DESCRIPTION

FIG. 1 is a perspective view of the upper portion of a bandage, showing the design;

FIG. 2 is a top view of the bandage of FIG. 1, showing the design;

FIG. 3 is a bottom view of the bandage of FIG. 1, showing the design;

FIG. 4 is a front elevation view of the bandage of FIG. 1, showing the design;

FIG. 5 is a left-side elevation view of the bandage of FIG. 1, showing the design;

FIG. 6 is a rear elevation view of the bandage of FIG. 1, showing the design; and,

FIG. 7 is a right-side elevation view of the bandage of FIG. 1, showing the design.

The broken lines in the drawings illustrate portions of the bandage and form no part of the claimed design.

1 Claim, 2 Drawing Sheets
